AIR-METHOD CLEANER SUPPORT

Daniel Benson Repleglo, Berkeley, Calif., assignor
to The Ohio Citizens Trust Company, as
trustee, Toledo, Ohio, a corporation of Ohio

Application August 6, 1936, Serial No. 94,653

1 Claim. (Cl. 248-1)

The invention relates to cleaning apparatus and more particularly to collapsible supporting devices for portable suction cleaners, particularly those of the air-method type which may be 5 selectively employed for floor cleaning purposes or by the use of suitable extension devices may be employed for cleaning walls, draperies, or the like.

Supports intended for this general purpose are 10 known and are shown, for example, in my prior patents, Nos. 1,862,941; 1,884,864; 1,884,865; 1,884,867; 1,884,870 and others, and it is the object of the present invention to provide an improved hinged support which may be swung to a working 15 position and by this swinging movement be expanded so as to provide a wide base or when the cleaner is to be placed in the closeted position the support may be moved out of the way and at the same time collapsed.

20 The invention will be more readily understood by reference to the accompanying drawings and the following detailed description, in which are set forth illustrative embodiments thereof:

In the drawings:

25 Fig. 1 is a side elevation, parts being in section, showing one form of cleaner equipped with the improved support in working position.

Fig. 2 is a side elevation of the same on a smaller scale and showing the cleaner in closeted position and the support collapsed.

30 Fig. 3 is an enlarged detail view of the portion of the cleaner shown in Fig. 2, parts being broken away, the support being shown collapsed in the full line position and expanded in the dash line position.

Fig. 4 is a view showing the cleaner in transverse section and the support in expanded position in full lines while the dot-and-dash lines show it in partially collapsed position.

40 Fig. 5 is a similar view showing the support fully collapsed.

Fig. 6 is an enlarged section taken on line 6—6 of Fig. 4.

Fig. 7 is a section taken on line 7—7, Fig. 4.

Fig. 8 is a detail view, partly in section, showing the mounting of the supporting rollers.

Fig. 9 is a detail view showing one of the cam lugs with which the cleaner is provided.

50 Fig. 10 is a detail view illustrating a step in the manufacture of the support.

Figs. 11, 12 and 13 are side elevations showing the support applied to a different form of cleaner, showing the cleaner in various positions which it may assume in service.

55 Referring particularly to Figs. 1-5, the refer-

ence numeral 10 denotes a cylindrical housing or caddy which may be composed of hard fiber, "Bakelite," metal or other suitable material, and which houses at its lower portion a power plant 11, including a motor and a fan driven thereby, the 5 caddy being provided with a removable cap 12 having a lateral outlet or outlets 13. The upper portion of the caddy houses the dust collecting and air filtering device which is shown as comprising an inner bag 14 composed of porous paper 10 and an outer re-inforcing receptacle 15 of cloth, wire or other relatively coarse fabric. The inner bag may be detachably secured to the neck 16 of the cap which is provided with a transparent cover 17. At the side of the cap and connecting 15 therewith is a valve 18 by means of which the interior of the caddy may be placed in communication with an upper or lower tubular member. The upper member 19 comprises a handle grip which likewise serves to turn the valve 18 when the member 19 is revolved axially. In the position of the valve shown a curved pipe 20 is in communication with the interior of the caddy, and this pipe is shown as provided with an extension 21 detachably secured to the member 20 by a suitable coupling 22, the extension 21 passing through a nipple 23 which may form part of the removable cap 12. To the opposite end of the pipe 21 may be detachably secured a floor tool 24, preferably of the type disclosed in my Patent 30 No. 1,994,868. The tubular members 19, 20 and 21 may be composed of hard fiber, "Bakelite," metal or other suitable material, although preferably a non-conductor of electricity is employed.

The cleaner is shown in the closeted position 35 in Fig. 2, with the caddy supported upright, and the handle member 19 turned at an angle to the position shown in Fig. 1 so that the extension 19 is placed in communication with the interior of the caddy. A bracket or hanger 25, similar to what is disclosed in my Patent No. 1,884,870 may be employed for supporting the upper end of the handle 19, such hanger being shown as equipped with an elbow member 26. The numeral 27 denotes a hose pipe or other extension which may be provided with suitable cleaning working tools and nozzles.

According to my invention the caddy 10 is encircled with a band 28, preferably at the lower portion of the caddy near the power plant since it is at this point that the weight of the apparatus is concentrated. The band may be adjustably held in position by means of a bolt 28-a passing through ears at the end of the band, as illustrated in Fig. 4. As is shown particularly in Figs. 55

4, 5 and 9, the band is provided with a pair of lugs 29 on opposite sides of the caddy, each lug having a divergent cam face 30 so arranged as to spread the legs 31 and 32 of the support when the 5 legs are brought to right angles to the body of the caddy. The legs are hingedly secured by means of hinge pins 33 extending into the lugs 29. The legs are composed of resilient material which is adapted to withstand torque and each 10 includes a web portion 34 of channel shape and each is provided with flat portions 35 and 36 on which there is no web. The legs are connected by a two-part brace member 37 hinged at 38 and constituting a toggle joint. The lower portions 15 of the legs are provided with telescoping members 39 and 40, respectively, which are parallel to the floor, the member 39 fitting over the member 40. Bumps or projections 41 are provided on the inner member while a pair of apertures or 20 indentations 42 and 43 in the outer member cooperate therewith and are adapted to serve as blind catches to hold the channel members either in extended or in contracted positions, as indicated in Figs. 4 and 5 respectively. Rollers 45 25 are provided which may be of the general type disclosed in my Patent No. 1,541,280, dated June 9, 1925, without the spring shank.

The center rivet or axle of the roller is riveted to the corners of the channel shaped legs, 30 which corners are reinforced so as to make them strong enough to sustain the riveted ends of the roller axle or spindle.

Operation

35 When the support is swung so that the legs are at right angles to the central axis of the caddy, it will be apparent that the cam action of the divergent face 30 of the lugs 29 to which the legs of the support are pivoted, will cause 40 the legs to spread to the fullest extent as illustrated in full lines in Figs. 1 and 4, and in dash lines in Fig. 3. A detent 46, projecting from the band 28 and located near the lugs 29 serves to limit the swinging movement. The legs are 45 forced apart to their limit and are held in such position by the brace 37 and by the bump or detent 41 in the inner channel member 40, engaging in the indentation 42 in the outer channel member.

50 To collapse the support the toggle connection is first broken at 38 as indicated in dot and dash lines in Fig. 4, whereupon the bracket may be swung to the inoperative position shown in Figs. 2 and 3 and fully collapsed, as indicated in Fig. 5.

55 It will be apparent that there is a torsion in the flat portions of the supporting legs and in the brace 37 but these parts being made of resilient material will withstand the torque and said torque tends to return the legs by a swinging action to the open position as soon as released. The blind catches in the channels 39 and 40 cause them to remain in open or in closed position but the catches may be overcome by the application of sufficient force.

60 In Figs. 11, 12 and 13, the support is shown as applied to a different form of cleaner. As illustrated, the reference character A denotes generally a floor tool which includes a motor housing 43, a fan casing 44 having an outlet 45 and an intake 60. A suction box 46 in the lower portion of the floor tool is separate from the interior of the fan casing and is provided with an outlet 47 for dust laden air.

65 Reference character B denotes generally a cylindrical housing or caddy hingedly connected

to the floor tool A by means of bracket members 48 and 49, while the interior of the caddy is connected to the fan casing inlet 60 by means of a collapsible tube 61 or equivalent device which permits the caddy to be swung in a vertical plane 5 with reference to the floor tool. The caddy houses a dust filtering device (not shown) which is preferably connected to a transparent removable cap or cover 50 and is adapted to be withdrawn therewith by means of a tubular member 51 which serves as a handle grip and also as an inlet pipe for dust laden air which is drawn into the dust filter within the caddy B. The handle 51 is preferably secured to the cap 50.

A flexible hose extension 52 is shown connected 15 to the end of the handle grip 51 and its opposite end may be connected to the outlet pipe 47 of the suction box, as illustrated in Fig. 12 or may be provided with a nozzle or other application tool 53 as illustrated in Figs. 11 and 13.

20 The caddy B is shown as equipped with a collapsible support C, similar to what has been described in connection with Figs. 1-10, inclusive, which is attached to the caddy by means of a band 54 surrounding the caddy and adjustably 25 connected as described in connection with Fig. 4. A suitable limiting stop 55 is provided on the band adjacent the point of attachment of the legs of the swinging support.

25 As illustrated in Fig. 11, the caddy is held in 30 vertical position by tightening the hinge connection between the bracket arms 48 and 49. The hose 52 may then be used for cleaning walls, draperies or the like, the bracket or support C being collapsed and swung out of the way. The 35 handle may, if desired, be supported by a suitable hanger, such as illustrated in Fig. 2.

30 In Fig. 12 the support C is shown swung to a position at right angles to the central axis of the caddy and in such position the legs are extended 40 by the cam action of the lugs to which the legs are secured. The bracket arms 48 and 49 are preferably loosely connected in this instance so that the caddy may be fully swung up or down. When swung downwardly the rollers of the member C may rest upon the floor and support the weight of the caddy in cooperation with the rollers of the floor tool, to facilitate movement 45 of the entire apparatus across the floor without the necessity for the operator bearing any of the 50 weight thereof.

55 In Fig. 13 the bracket C is shown as resting upon the floor and as supporting the caddy while the hose extension 52 and the working tool or nozzle may be used for floor cleaning or other 60 purposes. The tool 53 may be of the 90° angle type as shown in my Patents Nos. 1,403,524 and 1,994,871. Such tool may be removed when the hose pipe is to be connected to the outlet 47 of the suction box as in Fig. 12, and in such case 65 the member 53 may be attached to the end of the outlet pipe 45 and serve to direct air against the motor casing 43 to cool the same.

65 The invention has been described in detail for the purpose of illustration but it will be understood that variations and modifications may be resorted to without departing from the spirit of the invention.

I claim:

70 In a device of the character described, a tubular body member, and a collapsible and extensible hinged bracket adapted when extended to support the body member in inclined position, and when collapsed to permit the body member to lie flush against a plane surface; said bracket 75

comprising a pair of legs hingedly connected to the body member, a resilient flat strip connecting said legs intermediate their ends, said strip being pivotally connected at its ends to said legs and hinged intermediate its ends to form a toggle connection; means whereby the free ends of the legs are moved farther apart as the bracket is swung to operative position, and are moved closer

together when the legs are folded into inoperative position, and a pair of telescoping tubular members connecting the ends of the legs, said members having coacting means for holding the legs close together or spread apart in the collapsed or expanded positions respectively.

DANIEL BENSON REPLOGLE.
